UNITED STATES PATENT OFFICE

JOHN T. CORLEY, OF PROVIDENCE, RHODE ISLAND

TURRET STANDPIPE FOR FIRE HOSE

Application filed December 15, 1927. Serial No. 240,293.

This invention relates to an improved construction of turret standpipe for fire hose; and has for its object to provide in such a device a turret body member in which is swivelled a turret head member, this head member being of Y-shape with inturned end portions between which ends is pivotally mounted the nozzle whereby a universal movement of the nozzle is permitted to set the same in 10 different positions.

A further object of the invention is to provide a friction element between the connecting faces of the swing joint and the turret head and a nut for binding these faces together so that the nozzle is retained in any adjusted position relative to the head in which it swings.

The invention further consists in the forming of a face plate separate from the inturned 20 ends of the Y and securing this plate in position by molding or other fastening means, which construction greatly facilitates the threading and finishing of the inturned ends of the Y-shaped turret head.

25 A further object of the invention is the provision of a supporting bracket to receive the body portion of the turret head, this bracket being provided with supports adapted to rest upon a plain surface, the bracket also being provided with a concaved surface adapting it to fit and be clamped to a cylindrical standard by which the device may be either supported in operating position on a fire truck or clamped to a standard.

30 A still further object of the invention is to provide a set of legs on the device to support it on the ground when removed from its brackets.

35 With these and other objects in view, the invention consists of certain novel features of construction, as will be more fully described, and particularly pointed out in the appended claims.

In the accompanying drawings:

40 Fig. 1 is a top view of my improved device.

Fig. 2 is a side elevation showing the device as removed from its truck and supported on its legs on the ground with the nozzle in slightly raised position.

45 Fig. 3 shows the device as supported in

its brackets, the brackets resting upon a plain surface.

Fig. 4 shows the device as supported in its brackets and the brackets clamped in position to a standard.

Fig. 5 is a perspective view of two brackets designed to receive the turret standpipe device, said device being removed therefrom and these brackets supported on a plain surface.

Fig. 6 is an elevation partly in section showing the clamping bracket for engaging the turret body.

Fig. 7 is a top view of the lock which secures the clamp yoke in position.

Fig. 8 is an end view of the rear bracket showing the pins engaging the legs on the turret body, this bracket also being concaved to be mounted on a cylindrical standard.

Fig. 9 shows the clamp yoke which is arranged to cooperate with the bracket for securing the bracket on a cylindrical standpipe.

Fig. 10 is a front view showing a detail of the separate plate for the end of the Y-shaped turret head.

Fig. 11 is a central section thru this end plate showing its periphery as threaded and also the inner locking flange as being threaded or circularly grooved.

Fig. 12 shows this end plate as secured in position on the inturned ends of the turret head where it is in this case secured by being molded in position thereon.

Fig. 13 is an enlarged view showing a fragmental portion of this joint end turret head in section and illustrating a portion of the plate as secured in position on the inturned end of the turret head by being cast or molded therein; also showing the friction element between the engaging faces and a portion of the binding nut.

It is found in practice in the manipulation of fire hose in fighting fires, of advantage to provide a so-called turret standpipe of my improved construction with a bracket in which it may be clamped, the bracket being provided with means whereby it may rest upon and be secured to a plain surface such as on a fire truck to support the device in the desired position or whereby the bracket

may be removed from the fire truck and secured to a standard for supporting this nozzle; also it is found of advantage to provide a turret standpipe of this character, which is adapted to receive a universal movement and further it is found of advantage to so mount the nozzle in its revolving turret head that the nozzle may be supported at any desired elevation relative to the head in which it is mounted and be retained in such adjusted position without the necessity of being held by the firemen, leaving them free for other work. In a construction of turret head member of this character where it has inturned ends each facing the other, it is found to be very difficult to cut the screw threads on the periphery of these ends for the reception of the binding nuts, and to obviate this structural difficulty, I have formed separate and independent end plates which have been previously finished and threaded and have molded these end plates into the ends of this turret head when the latter is cast, thereby materially reducing the time and labor necessary for the finishing operation of this member of the device; and the following is a detailed description of the present embodiment of my invention and showing one arrangement of parts whereby these advantageous results may be accomplished:

With reference to the drawings, 10 designates the turret body member of my improved device, which is formed at one end with a double hose connection as at 11 and at 25 its opposite end with a swivel joint portion 12 in which is rotatably mounted the turret head member 13 and which is rotatably held therein by means of a nut 14. This turret head member is preferably in Y-shape, the 40 ends of the branches being turned inwardly toward each other, as at 15, and each of these inturned ends is provided with a separate end plate 16 which is formed in disc shape, see Figures 10 to 13 inclusive. This disc has a 45 peripheral flange 17 which is threaded on its outer surface and also on its inner surface 18. This plate also has an inner flange 19 threaded on both its inner and outer surfaces. These internal threads serving to simply 50 roughen the surface to lock the plate in the ends of the Y when the metal is flowed around the same in casting the plates in these ends. These plates are finished prior to being cast into position in the turret head and by this 55 construction, it will be seen that the finishing of this Y-shaped turret head is greatly facilitated, as owing to its shape it is very hard to handle and special tools and fixtures must be provided with which to finish the 60 surface and thread its peripheries, the cost of which is greatly reduced by my improved arrangement of forming separate end plates and securing them in position by a molding operation. These plates may be secured by 65 other than a molding operation if desired.

The swing joint member 20 of this device has oppositely turned inlet portions 21, the ends of which are faced and in some cases grooved to receive a packing ring 22 and these ends are flanged as at 23 to receive a 70 nut 24 by which these ends are bound against the faces of the turret head, the packing members 22 between serving to prevent leaking and also as a friction element to retain this nozzle in any adjusted position without the necessity 75 of being supported by the firemen who may leave this device when once set to continue its work while they busy themselves in other directions.

In some instances, it is found of advantage 80 to provide a bracket or a set of brackets in which this turret standpipe may be supported either on the truck where it may be used effectively or removed from the truck and secured in position on a standard of cylindrical or 85 other shape, such as is often found on roofs, or to pipes, lamp posts, or the like, in the vicinity of the fire; and to accomplish this in a simple and effective way, I have formed a bracket 25 which is provided with spaced 90 pins 26 to engage openings in the legs 27 on the turret body. This bracket is provided with supporting feet or flanges 28 which may be bolted to a plain surface, illustrated by the member 29, and this bracket is also concaved 95 as at 30 to receive a cylindrical standard; also, I have provided a second cooperating bracket 31 which has a clamp yoke 32 pivoted at 33 for embracing the turret body and this yoke is arranged to be secured in position 100 by means of a lock 33 which when swung into one position secures the clamp closed and when swung into another position releases the clamp to be swung back and permit the quick removal of the turret body from these 105 brackets.

The bracket 31 is also provided with feet 34 which may be bolted to a plain surface 29 which in this case illustrates the surface on the fire truck and the bracket is provided 110 with a concaved portion 35 which permits it to cooperate with the clamp member 36, whereby it may be secured by bolts thru the flanges 34 to a cylindrical standard 37, as illustrated in Fig. 4, or other similar convenient support.

I have shown a pair of brackets as arranged to support the device but in some instances a single heavier bracket similar to bracket 31 may be employed if desired.

In some instances, it is found of advantage to remove the device entirely from these brackets and place it on the ground within working distance of the fire and in this case the members 27 on the turret body serve as legs for supporting this portion of the device and I have also provided a pair of spaced legs 38 on the head member which cooperate with those on the body and serve to also steady this portion of the device and when 130

resting upon these four legs the reaction of the water from the nozzle when inclined upwardly serves to bind these legs securely against the ground or other supporting surface with such force that they will not move.

5. My improved turret standpipe is very practical in its construction and operation and serves as an effective fire fighter requiring the minimum amount of attention from the firemen.

10. The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A turret standpipe for fire hose, comprising a tubular turret body member, a Y-shaped head member mounted to swivel in said body member, a nozzle pivotally mounted in said head member, and a plurality of spaced supporting members positioned respectively on opposite sides of said swivel connection for supporting, steadyng and retaining the same on the ground when the nozzle is inclined upwardly and under action.

2. A turret standpipe for fire hose, comprising a tubular turret body member, a head member mounted to swivel in said body member, a nozzle pivotally mounted in said head member, widely spaced supporting members on said head member for steadyng the device on its base while in action, and cooperating supporting members on the body member for further assisting in steadyng the whole device on its base when in action.

3. A turret standpipe for fire hose, comprising a tubular turret body member, a Y-shaped head member mounted to swivel in said body member, a nozzle having a swing joint member with oppositely outturned inlet ends pivotally mounted between the opposite faces of said inturned ends of the Y, a binding nut for rotatably securing said adjacent ends together, and a plurality of spaced supporting legs positioned respectively on opposite sides of said swivel connection for supporting, steadyng and retaining the same on the ground when the nozzle is inclined upwardly and under action.

4. A turret standpipe for fire hose, comprising a tubular turret body member, a tubular yoke-shaped head member mounted to swivel in said body member, a nozzle having a swing joint member pivotally mounted between the opposite faces of the branches of said yoke, means at the swinging joint for retaining the nozzle in any adjusted position relative to the head member, widely spaced supporting legs on said head member for steadyng the device on its base while in action, and cooperating supporting legs on the body member for further assisting in

steadyng the whole device on its base when in action.

5. A turret standpipe for fire hose, comprising a tubular body member, a fluid coupling at one end thereof a Y-shaped head member mounted to swivel in said body member at the other end thereof, a nozzle mounted in said head member, and spaced body member supporting elements associated with said members for supporting, steadyng and retaining the same on the ground when in action, the mounting of said parts enabling the adjustment of the nozzle in a vertical plane.

In testimony whereof I affix my signature. 80
JOHN T. CORLEY.
